UNITED STATES PATENT OFFICE

WILLIAM F. MCPHEE, OF CHICAGO, ILLINOIS

BOILER CONSTRUCTION

Application filed October 10, 1930. Serial No. 487,853.

My invention relates to improvements in boiler constructions, and it consists in the combinations, constructions, and arrangements herein described and claimed.

5 An object of my invention is to provide a boiler construction in which a novel fin structure is employed whereby a maximum heating surface is attained, and in which the general boiler design is such that oil or gas burners may be effectively employed.

10 A further object is to provide a boiler in which the fin construction is arranged in such a manner that these elements serve a double function as supporting and reinforcing elements.

15 A further object is to provide a boiler construction designed in such a manner that the necessity for stay bolts and similar bracing is entirely dispensed with, irrespective of the 20 capacity of the boiler.

25 Other objects and advantages will appear in the following specification, and the novel features of the invention will be particularly pointed out in the appended claims.

30 My invention is illustrated in the accompanying drawings, forming part of this application, in which

Figure 1 is a sectional view of a boiler embodying my invention,

35 Figure 2 is a sectional view taken along the line 2—2 of Figure 1, and

Figure 3 is a diagrammatic front elevation of the boiler.

40 In carrying out my invention, I make use of a shell 1, which, in the present instance, is circular in cross section and domed as at 2. The bottom end of the shell is disposed within a flange 3 associated with a base 4. The latter is provided with a burner chamber 5 and a second chamber 6 which communicates with a flue 7. The burnt products of combustion pass to the chamber 6 and therefrom through the flue 7. The base is provided with a second flange 8 adjacent to which a 45 cylindrical member 9 is positioned. This member is provided with a plurality of openings 10, see Figure 2, in its wall for receiving fins 11. The sides of the fins and their lower ends are preferably positioned within the openings 10 and may be connected with

the member 9 by welding. The fins, as will be seen in referring to Figure 2, are radially aligned. An opening 12 is provided in the side of the boiler for permitting access to the interior of the fire box. A door 13 may be 55 arranged for closing the opening. This door may be provided with suitable dampers. Certain of the fins are slightly shorter than the remaining fins for permitting the construction of the opening 12 in the side of 60 the boiler. In the present layout, two of the fins are shortened. In other respects these two fins are identical with the remaining fins.

65 A crown sheet 14 is secured to the upper ends of the fins. The crown sheet is preferably provided with openings conforming to the shape of the fins for receiving the ends of the latter. The fins may be welded to the crown sheet. The crown sheet is provided with a flange 15 having a ring 16 which projects inwardly. The edge of the ring bears 70 against the edges of the fins.

75 The cylindrical member 9 may be welded to the ring. The portions of the fins which are disposed above the ring 16 are closed upon their sides by means of closure plates 17. These plates may be also welded to the fins.

80 The outer diameter of the ring 16 is somewhat larger than the diameter of the member 9. The ring is cut out for receiving the upper 85 ends of a plurality of hollow curved members 18. These members are secured within openings 19 in a web 20 which forms a part of the base 4. The lower ends of the members 18 may be welded within the openings 19. It will thus be seen that the interior of the 90 member 9, which may be termed an inner shell, is placed in communication with the chamber 6 through the medium of the members 18. The burnt products of combustion from the interior of the boiler may pass downwardly through the members 18 into the chamber 6 and through the flue 7.

95 The boiler may be provided with a water glass 21, see Figure 3, and a plurality of tricocks 22. The boiler in the present instance is provided with a water and steam chamber 23 above the crown sheet 14. The boiler may be provided with inlet pipes 24, outlet pipes 25, and a clean-out plug 26. The boiler may 100

also be provided with a pressure gauge 27. Such devices are of course well known in the art and require no detailed description.

In operation, a burner of any suitable type is placed within the chamber 5. This chamber, together with the interior of the member 9, may be defined as a combustion chamber. The specific construction disclosed in the present instance is primarily designed for use in connection with oil and gas burners. The structure may be narrowed upwardly rather than having the fins arranged in parallelism as shown in Figure 1. In other words, the upper ends of the fins may be arranged closer together than the lower ends.

Any suitable type of oil or gas burner may be positioned in the chamber 5. This chamber may also be lined with fire brick, if desired. The base may also be provided with openings 20 for receiving conduits and the like associated with the burner structure. In the present instance I have not shown a burner since there are many burners manufactured which may be employed. The base is provided with a door 28 for permitting access to the chamber 5.

The fins are positioned so that the heating surfaces provided by these elements are positioned where the heat is most intense. The 30 fins are also arranged so that a central opening 29 is provided, see Figure 2. Flames in a boiler of this type tend to move toward the center of the device and work upwardly. The arrangement of the fins is such that the flame 35 and the burnt products of combustion may move freely and at the same time a maximum heating efficiency is provided. The burnt products of combustion pass upwardly, downwardly through the members 18, and 40 from the boiler through the flue 7.

Water circulates between the inner shell 9 and the outer shell 1 and around the members 8. The fins communicate with the space between the two shells. Water may circulate 45 upwardly through the fins and into the chamber 23.

I claim:

1. A boiler construction comprising a base having a flue chamber, an inner shell and an outer shell disposed upon the base and arranged in spaced-apart relation, a crown sheet having a cylindrical portion of large diameter than the inner shell and a ring secured to the latter, said inner shell being provided with 50 openings in its side, a plurality of hollow fins secured to the inner shell and having open sides communicating with the openings in the inner shell, the outer edges of said fins being substantially aligned with the inner edge of said ring, the upper ends of the fins being open and communicating with openings in the crown sheet, plates for closing the open side portions of the fins extending between the ring and the crown sheet, and plurality 55 of hollow curved connected with said ring and

the base for placing the interior of the inner shell in communication with said flue chamber.

2. A device of the character described comprising a base having a combustion chamber and a flue chamber, a housing mounted on the base, a casing mounted on the base and disposed within and in spaced-apart relation with respect to the housing for providing a compartment therebetween, said casing having an open bottom end for providing communication between the interior of the casing and the combustion chamber, longitudinally extending and radially positioned hollow casing portions connected with the casing on the interior thereof, said casing being provided with openings therein for providing communication between the interior of the casing portions and said compartment, a partitioning portion connected with the top portion of the casing for providing an auxiliary flue chamber therebetween, said auxiliary flue chamber being in communication with the interior of the casing, and hollow members for providing communication between 80 said flue chambers.
